UNITED STATES PATENT OFFICE.

ARCHIBALD K. LEE, OF GALVESTON, TEXAS.

IMPROVEMENT IN DISTILLING TURPENTINE.

Specification forming part of Letters Patent No. 131,550, dated September 24, 1872; reissue No. 5,351, dated April 15, 1873; application filed April 8, 1873.

To all whom it may concern:

Be it known that I, ARCHIBALD K. LEE, of Galveston, in the county of Galveston and State of Texas, did invent certain new and useful Improvements in Apparatus for Distilling Turpentine, on which Letters Patent of the United States were granted bearing date September 24, 1872, and numbered 131,550; and that the following is a full, clear, and exact description of said invention, reference being had to the accompanying drawing and the letters of reference marked thereon making part of this specification, in which is represented a vertical sectional view of my apparatus.

The object of my invention consists in so constructing the apparatus as to permit of a continuous distillation, or in so arranging the apparatus that so soon as the crude turpentine is liquidized it is conveyed to a suitable chamber, and from which it is at pleasure fed to the still, thus permitting each and every stage of the process of distillation being carried on in the apparatus at one and the same time, the still evaporating the crude turpentine fed from the intermediate chamber or reservoir while the liquidizing-chamber, reservoir, and still are connected by means of valves and a jacketed pipe in such manner that the contents of the one are readily fed to the other, as occasion requires, which insures an uninterrupted action of the apparatus throughout the different stages of the process of distillation. My improvement also consists in so arranging and securing a pipe in connection with the steam-coil of the still and the reservoir and liquidizing-chamber that the steam which aids in the evaporation of the crude liquidized turpentine shall serve to preserve the desired and uniform temperature in the intermediate chamber and reservoir, and also aid in supplying the necessary heat to liquidize the crude material. My improvement also consists in surrounding the lower section of the still with a jacket, in such manner as to provide a superheating steam-chamber, and from which the coil within the still is supplied, and in so arranging the still and jacket, in connection with the fire-pot of the furnace, that while the jacket protects the still from the direct action of the heat, yet the

same shall so act on the jacket itself as to cause the steam in its passage through the chamber which the jacket forms, and as it passes around the lower section of the still, to become superheated. My improvement also consists in surrounding the interior wall of the liquidizing-chamber with a perforated coil, and in providing the same with a revolving rake or stirrer, which is operated through a vertical shaft having its bearings at the center of said chamber. Practical experience has shown that the continued agitation of the mass in connection with the jets of steam from the perforated coil and the heat communicated from the coil of the still combined insure the most rapid liquidization of the mass of crude material. My invention also consists in connecting the still and liquidation-chamber each with the separator by means of pipes, which lead, respectively, from the upper section of these vessels to the lower section of the separator, and which permits the vapor, as rapidly as it is generated in either of the vessels, being conveyed immediately to the separator, and also in providing the pipe which leads from the still with an egg or expanded joint which receives the heavier liquid particles which may be thrown off from the evaporating-chamber of the still. My improvement also consists in connecting a separator, constructed as hereinafter described, with a vessel so arranged as to receive the pyroligneous-acid water and other impurities as they are separated from the vaporized material, thus saving the same and providing an article of commerce heretofore wasted in devices of this character. My improvement also consists in conveying the turpentine from the condenser to a close vessel, so arranged as to secure the entire separation therefrom of all condensed steam, and in then passing the turpentine to another close vessel, from which it is barreled.

The great advantage of this arrangement of vessels in connection with the condenser is that all danger of evaporation is securely guarded against, and a purer article is produced in consequence.

The construction and operation of my invention are as follows:

A is a furnace, and A' A' the grate-bars, which may be of any desired form or pattern, and are constructed in the usual manner. B

is the still, which is constructed out of any suitable material, and at its lower section or base is of a concave or circular form. Within the vaporizing-chamber of the still B is arranged an ordinary coil, B', and around the outer curved surface of the still is a jacket, C, which is so arranged in connection therewith as to leave or furnish a superheating steam-chamber, C'. Steam from a boiler suitably arranged is, by means of the pipe C², supplied to this chamber C', and after passing under and around the lower section of the still B by means of the pipe C³ is conveyed to the coil B'.

By reference to the drawing it will be seen that, in consequence of my arrangement of the still B and jacket C in connection with the fire-pot of the furnace, while the jacket C entirely protects the still B from the direct action of the heat, yet the same is itself so acted on as to insure the superheating of all steam admitted through the pipe C² as it passes through the chamber C', and, consequently, under and in direct contact with the still B, in which superheated condition through the pipe C³ it is fed to the coil B'. D is a chamber, and is divided into two compartments, the upper one, D¹, being a liquidizing-chamber, into which, by means of a man-hole, D², the crude turpentine is supplied, and the lower one, E, being a reservoir, into which the crude turpentine, after being sufficiently liquidized, is allowed to pass by means of the valve D³, which is opened and closed at pleasure by the valve-rod and lever D⁴. From this reservoir E, by means of the valve E¹ and jacketed pipe E², the liquidized crude turpentine is fed, as occasion may require, to the evaporating-chamber of the still B. This valve E¹ is operated so as to be opened and closed at pleasure, by means of a valve-rod and lever, E³. Within the liquidizing-chamber D¹ is secured, on a vertical shaft, F¹, the rake or stirrer F. The shaft is secured so as to revolve freely in suitable bearings on the upper and lower surfaces of the chamber and at the centers thereof, while the rake or stirrer F is constructed of any suitable material, and is of the form clearly shown on the drawing. Around the interior wall of this chamber D¹ is a perforated coil, F², which is designed to emit jets of steam through the mass of crude turpentine, to aid in its liquidization, while the same is being continually agitated by the revolving rake or stirrer F. G is a pipe connected with the coil B', by means of which the superheated steam is conveyed from the coil up through the upper section of the still B, and thence to the reservoir E, where it serves to maintain the liquidized turpentine at a uniform temperature, and thence to the chamber D¹, where it aids in liquidizing the crude material. The sections of this pipe G, which are within the reservoir E and chamber D¹, are perforated, as clearly shown at G¹ G². H is the separator, and consists of a column having a series of trays or partitions H¹ H², having openings

at their centers, over which are deflecting caps H² H². Immediately below these caps are openings or orifices leading into the interior chamber of the separator, which allow of the free passage of all the products of evaporation which are driven into the separator. Through an opening in each of the trays H¹ H¹ is secured a pipe, H³, the upper section of which is immediately below the orifice through which the caps H² H² deflect the vapors, acid, &c. At the upper section of the still B and the liquidizing-compartment D¹, and communicating with the interior chambers thereof, are vapor pipes or tubes I and I¹, which lead directly to the separator H, entering the same at the lower section thereof, as clearly shown in the drawing. Through these pipes are fed the material as fast as the same is evaporated. The pipe I is provided with an egg or expanded joint, I², which receives any heavy liquid particles which may be driven with the vapor from the still. The chamber which this expanded joint forms is emptied at pleasure by means of the stop-cock I³. K is a receptacle, which is connected with the separator by means of the pipe K¹, and into which the pyrolytic-acid water, which is thrown off from the vapor in its passage through the separator, is collected instead of being wasted, as heretofore has been the practice. From the center of the dome of the separator leads a pipe, L, which communicates directly with the condensing-worm L¹, and which is of ordinary construction, and incased in a water-tight tank or vessel, L², in the usual manner. The worm L¹ is kept constantly immersed in fresh water by means of the supply-pipe L³. As the water becomes heated it rises, and is discharged through the pipe L⁴. From the worm L¹ the condensed vapor or turpentine is led to a receptacle, M, by means of a pipe, M¹, which enters the receptacle M at the lower section of the same. This receptacle M, in a certain sense, also really acts as an additional separator, as in this vessel the steam which may have remained with the vapor and been condensed in the worm is separated from the turpentine and drawn off at pleasure by means of the cock M². The turpentine is conveyed to the vessel N by means of the pipe N¹, from which it is drawn off for barreling by means of the cock N². The still B is provided with a thermometer, O, and a proof-stick, O'; and from the center of its concave section, and passing through the steam-jacket C, leads a pipe, P, which is provided with a stop-cock, P¹. P² is a sliding valve, which is operated by means of a rod and lever, P³. This valve P² permits the operator at pleasure to open or shut off the communication between the still and the pipe P. Through this pipe P the resin in a liquid condition is drawn off into the strainer R, and thence to the resin-box R'. The various features of this apparatus are supported or sustained on any suitable framework.

From the foregoing description the operation

of the apparatus will be readily understood. The crude material is poured into the chamber D¹, and steam is supplied to the perforated coil F². Motion is then imparted to the shaft F¹, which revolves rapidly the rake or stirrer F. This rapid agitation of the mass by the rake, in connection with the jets of steam and the heat from the section G² of the pipe G, in a short time liquidizes the mass. So soon as this is sufficiently done, the valve D³ is opened by the lever and rod D⁴, and the crude turpentine, in a liquid state, passes to the intermediate chamber or reservoir E. Thus the chamber D¹, being emptied, is in condition to be recharged, which is immediately done. In the vessel E the liquid turpentine is preserved at the desired temperature by means of the section G¹ of the pipe G. The coil B¹ is continually supplied with superheated steam from the chamber C¹. The valve E¹ is now opened by means of the valve-rod and lever E³, and through the jacketed pipe E² is supplied to the still B the liquidized turpentine, where, at an exceedingly low temperature, its evaporation is insured. By means of the steam-chamber C¹, coil B¹, and the lower section of the pipe G, as rapidly as the evaporation takes place the vapor is fed, by means of the pipe I, to the separator H, as is also any vapor which may be generated in the liquidizing-chamber D¹, by means of the pipe I¹. Entering the chamber of the separator, it passes up through the opening in the lower tray H¹, and, striking against the cap H², is deflected and escapes by the orifice immediately below the cap again out into the chamber and up through the next, and so on throughout the entire series. But in the passage of the vapor through each of these partitions or trays H¹ and under the deflectors H² it is robbed of more or less of its pyroligneous-acid water, and other impurities, which, being heavier than the vapor, falls and accumulates on the trays, while the vapor continues its ascent. But this acid water and the other impurities can only accumulate to a certain depth, because so soon as they reach a point flush with the upper openings of the pipes H³ H³ they begin to flow down from one tray to another until they reach the bottom of the separator H, from which they are conveyed by the pipe K¹ to the vessel K, to be drawn off as wanted by means of the cock K². The vapor, thus now comparatively free from the acid water, is conveyed by the pipe L to the worm L¹, where its condensation takes place. But in the process of condensation of the turpentine considerable steam or moisture has also been condensed, of which it is most desirable to free the turpentine; therefore, from

the worm L¹ the turpentine and condensed steam are conveyed together to the vessel M by means of the pipe M¹, which pipe enters at the lower section of the vessel. The water, being heavier than the turpentine, remains at the bottom, and the turpentine rises until it reaches the opening through which enters the pipe N¹, by which pipe, in a pure state, the turpentine is conveyed to the vessel N, and from which it is drawn off into barrels. The liquid resin from the still, the pyroligneous-acid water from the vessel K, and the condensed water from the vessel M are all drawn off, as clearly shown.

From the foregoing description it will readily be seen that each and every stage of the process is carried on in the apparatus at one and the same time.

What I claim as new, and desire to secure by Letters Patent of the United States, is—

1. The still B, closed coil B¹, jacket C, and pipes C² C³, when the same are combined as shown, and arranged in connection with a suitable furnace to operate substantially as described.

2. In combination with the coil B¹, the pipe G, the same being arranged to operate in connection with the still B, reservoir E, and liquidizing-chamber D¹, substantially as described.

3. The liquidizing-chamber D¹ having its interior wall surrounded with a perforated coil, F², and the revolving rake F, when the same are so combined and arranged as to operate substantially as described.

4. The chamber D¹, reservoir E, still B, valves D³ and E¹, and the jacketed pipe E², the whole being constructed and arranged to operate substantially as described.

5. The vapor-pipe I, having an expanded joint, I², and cock I³, when the same is connected with the still and separator in such manner as to operate substantially as described.

6. The separator H, vessel K, condensing-worm L¹, pipes L K¹, the same being so constructed, combined, and arranged as to operate substantially as described.

7. The condensing-worm L¹, vessels M N, and pipes M¹ N¹, the same being so constructed, combined, and arranged as to operate substantially as described.

In testimony whereof I have signed my name to this specification before two subscribing witnesses.

ARCHIBALD K. LEE.
